(57) **CLAIM**

The ornamental design for a brace, as shown and described.

DESCRIPTION

FIG. 1 is a perspective view showing the new design for a brace;

FIG. 2 is a front view thereof;

FIG. 3 is a right side view thereof, a left side view being a mirror image thereof;

FIG. 4 is a top view thereof;

FIG. 5 is a rear view thereof; and,

FIG. 6 is a bottom view thereof.

The portions of the brace shown in broken lines form no part of the claimed design.
